INVENTOR.

UNITED STATES PATENT OFFICE.

ERNEST HOPKINSON, OF NEW YORK, N. Y.

APPARATUS FOR BUILDING PNEUMATIC TIRES FOR AUTOMOBILES.

1,289,775.

Specification of Letters Patent. Patented Dec. 31, 1918.

Continuation of application Serial No. 145,591, filed January 31, 1917. This application filed October 16, 1918. Serial No. 258,439.

To all whom it may concern:

Be it known that I, ERNEST HOPKINSON, a citizen of the United States, and a resident of the city, county, and State of New York, have invented new and useful Improvements in Apparatus for Building Pneumatic Tires for Automobiles, of which the following is a full, clear, and exact description.

10 This invention relates to apparatus for building tires, more particularly, apparatus for imparting the desired shape to the assembled components of a tire casing, and is a continuation of my former application 15 filed January 31, 1917, Serial No. 145,591.

15 The object of this invention is to provide an apparatus capable of imparting substantially circular cross-sectional shape to the built-up components of a tire, previously assembled in the form of a pulley band.

20 For a clearer understanding of my invention, reference is made to the following description and the accompanying drawings, in which—

25 Figure 1 is a view partly in side elevation and partly in section illustrating my apparatus;

30 Fig. 2 is a view partly in section and partly in perspective showing the retaining ring of my apparatus in unlocked position; and

35 Fig. 3 is a similar view showing the same in locked position.

Referring to the drawings, the framework 35 of the machine consists of uprights 1 and a cross-piece 2. Extending from the cross-piece to the base and mounted in suitable thrust bearings 3^a are two threaded rods 3, each of which has secured to it a bevel-gear 4 meshing with a bevel-gear 5 on the shafts 6, each of which shafts carries a bevel-gear 7, driven by bevel-gear 8 which is connected by any suitable means to a source of power. Centrally located between the uprights 1 is 40 a drum or cylinder 9 on which rests a second drum in the form of a removable ring 10, which in turn supports a removable ring 11. The abutting edges of the drums 9, 10 and 11 are stepped or otherwise adapted to 45 interfit in such a way that lateral displacement is prevented and a flush smooth outer joint provided. Thus when in position they 50 form one continuous drum or cylinder, hav-

ing a vertical axis, and sections which maintain their relation without other retaining means than their own weight. The middle drum or ring 10 is provided with a central circumferential channel 12 in which is seated an expansible tube 13 having an inflating valve 14. On either side of the ring 10 and 55 equally distant from its central line is provided a forcing ring 15 supported by arms 16 having a threaded engagement with the rods 3, said rings being adapted to be uniformly moved toward and away from each 60 other and the channel 12 by actuating the rods 3. Encircling the cylinder 9 and the ring 11 respectively, are flanges 17 adapted to be forced toward each other by the projecting outer edges 15^a of the rings 15 onto 65 the drum or ring 10 where they are locked against outward movement by the engagement of the retaining rings 18 with the 70 grooves 19. The flanges 17 are of substantially right-angled cross-sectional shape, one 75 leg of the angle forming an inward extension 17^a lying adjacent the surface of the drum, and the other 17^b projecting laterally outward from the drum a sufficient distance 80 to permit its engagement by the overhanging edge 15^a of the ring 15, while the retaining or locking ring 18 is carried along in the undercut portion thereof.

The operation of my device is as follows:

The various fibrous, filamentary, or woven 85 fabric elements of a tire carcass are assembled together with the usual inextensible bead wires or bead cores in the form of a flat pulley band. This assembly is preferably carried out on an expansible drum. 90 Preferably the cushion stock, breaker strip, and tread portions of the tire will be assembled on the carcass while in the flat pulley band form.

Having the tire built up as above described, the rings 15 of the machine are separated to their positions farthest apart from each other (the position of the upper ring indicated in dotted lines, Fig. 1) and the ring 11 is entirely removed. The ring 100 10 with the tube 13 deflated thereon is left in place resting on the cylinder 9. The lower flange 17 and its locking ring 18 are then placed in position resting upon the lower ring 15. The pulley band carcass or 105 casing, formed as above described, is then

- placed about the drum as shown in full lines in the drawing, the ring 11 is seated above the ring 10, and finally the upper flange 17 and locking ring 18 are placed in position.
- 5 Power is then applied to the gear 8, which causes the rods 3 to turn, moving the forcing rings 15 and the flanges 17 toward each other until they contact with the edges of the flat casing. The pitch of the threading 10 on the rods 3 is such that the inner edges of the forcing rings are always kept uniformly distant from the central circumferential line of the channel 12 and therefore when the flanges 17 have been moved into contact with 15 both edges of the pulley band, the latter has been accurately and evenly centered about the inflating tube 13. A further movement of the rings 15 acts to force the extensions 17^a of the flanges 17 under the edges 20 of the pulley band, forcing them slightly outward from the surface of the drum, so that there is a clearance between the inner surface of the pulley band casing and the outer surface of the rings. This clearance is 25 essential in most types of construction. However, there are instances in which it may be preferable to force the edges of the band together by sliding them along the surface of the drum.
- 30 The further movement of the forcing rings 15 is accomplished simultaneously with the admission of compressed air to the inflatable tube 13, which forces the central portion of the pulley band radially outward 35 as the forcing rings 15 move the edges of the casing toward each other to circumferential lines on each side of the channel 12 immediately above and below the lower and upper grooves 19 respectively. As pointed 40 out above, the progressive movement of the two rings 15 is at all times coincident, so that throughout the forming operation the edges of the pulley band have been maintained equidistant from the central circumferential line of the channel 12. The central line of the band has therefore been forced 45 radially outward, thus causing the band to assume a symmetrical cross-sectional shape at all stages of the forming operation.
- 50 In forcing the flanges 17 together, the overhanging edges 15^a of the rings 15 have contacted directly against the outer faces 17^b of the flanges 17. Consequently, the locking rings 18 are loosely held between the 55 latter parts, and as soon as the flanges 17 clear the grooves 19, they (the rings 18) snap into place therein.
- The machine is then reversed and the 60 forcing rings 15 are separated a slight distance. The internal air pressure forces the edges of the casing a slight distance apart, which pushes back the flanges 17 into the 65 positions shown in Fig. 3, where they are held against further separation by their engagement with the locking rings 18 now

seated in the grooves 19. The admission of air into the inflatable tube 13 is continued, however, until the casing is caused to assume a shape in dotted lines in Fig. 1.

The reverse movement of the gear 8 is 70 now continued to further move apart the forcing rings 15 until in their farthest separated positions; when the ring 11 is lifted off the ring 10, which is next removed, carrying with it the casing and inflated tube 75 locked in position thereon by interengagement of the flanges 17, rings 18 and grooves 19.

The tire may now be finished according 80 to any preferred method. In case the shaping operation has been applied to the carcass only, it is of course necessary to next apply the cushion stock, breaker strip and tread stock. On the other hand, if the latter elements have been built into the flat 85 pulley band, the tire is now ready for vulcanization, which may be accomplished by any of the well known methods.

In practice several duplicate rings, flanges, etc., are provided, so that the operation of 90 the machine may be continued without waiting for the removal of the casing from the ring upon which it was shaped. I also contemplate forming the cylinder 9 in several sections, the uppermost being similar to the 95 ring 11. In this way the ring 10 may be assembled with the two rings on either side of it, the flat pulley, and the flanges, apart from the machine, and the thus assembled structure put in place thereon as a unit. 100

Having thus described my invention, what I claim and desire to protect by Letters Patent is:—

1. A tire building machine, comprising a drum adapted to support a pulley band of 105 rubber and fibrous material to be formed into tire shape, an inflatable tube supported on said drum underneath the pulley band, means for moving the edges of the pulley band toward each other to a predetermined 110 position, and means for holding said edges in such position.

2. A tire building machine, comprising a drum with a removable central portion 115 grooved to receive an inflatable tube, side flanges, and means for securing the side flanges on the removable portion of said drum.

3. A tire building machine, comprising a drum with a removable central portion, side 120 flanges, and means for moving said flanges onto said central portion of the drum, and means for securing said flanges thereon.

4. A pneumatic tire building machine for 125 converting an annular flat pulley band into a tire of substantially U-shaped cross-section, comprising means for engaging the edges of said band while in flat condition and moving said edges toward each other, in combination with means adapted to force 130

the central portion of the tire radially outward while said edge portions are being moved toward each other.

5. A pneumatic tire building machine for converting an annular flat pulley band into a tire of substantially U-shaped cross-section, comprising means adapted by positive engagement with the edge portions of said band to bodily move the said edge portions 10 toward each other, in combination with means adapted to force the central portion of the tire radially outward.

6. A tire building machine, comprising means for forcing the edge portions of a tire 15 casing toward each other, means adapted to force the central portion of the tire radially outward while said edge portions are being forced toward each other, and means for securing said edge portions against outward 20 movement.

7. A tire building machine, comprising a cylinder, flanges encircling said cylinder, means for forcing said flanges toward each other, and means for locking said flanges 25 against outward movement.

8. A tire building machine, comprising a cylinder having a circumferential channel, flanges encircling said cylinder on either side of said channel, an expandible tube 30 located in said channel, means for moving said flanges toward said channel, and means for expanding said tube.

9. A tire building machine, comprising a cylinder having a circumferential channel, 35 flanges encircling said cylinder on either

side of said channel, an expandible tube located in said channel, means for moving said flanges toward said channel, means for expanding said tube, and means for locking said flanges against outward movement. 40

10. A tire building machine, comprising a vertical cylinder, flanges encircling said cylinder, means for forcing said flanges toward each other, and means for locking said flanges against outward movement. 45

11. A tire building machine, comprising a plurality of superposed rings forming a cylinder, flanges encircling the cylinder, means for forcing said flanges toward each other, and means for locking said flanges on 50 one of said rings.

12. A tire building machine, comprising a cylinder adapted to support a pulley band of rubber and fibrous material to be formed into tire shape, and means for maintaining 55 the edge portions of said band clear of said cylinder while moving them toward each other.

13. A tire building machine, comprising a cylinder, flanges encircling said cylinder 60 adapted to force the edges of a tire casing toward each other, said flanges having inwardly projecting extensions adapted to support the edges of the casing clear of said cylinder, and means for moving said flanges 65 toward each other.

Signed at New York, county and State of New York, this 9th day of October, 1918.

ERNEST HOPKINSON.
